UNITED STATES PATENT OFFICE

JOHN M. MILLER, OF PHILADELPHIA, PENNSYLVANIA, ASSIGNOR TO ATWATER KENT MANUFACTURING COMPANY, OF PHILADELPHIA, PENNSYLVANIA, A CORPORATION OF PENNSYLVANIA

SYSTEM OF REACTION CONTROL

Application filed July 23, 1925. Serial No. 45,481.

My invention relates to the control, reduction or elimination of reaction of one circuit or path upon another, particularly as regards high or radio frequency currents as utilized in systems of radio communication or in high frequency carrier wave systems utilizing conductors between stations.

In accordance with my invention, the reaction upon the input circuit of a three electrode thermionic device by disturbing electro-motive-forces in its anode circuit or in a remote circuit is controlled, reduced or eliminated by so utilizing inductances as to define a point in the input, output or related circuit at which the potential variations caused by the reaction are in phase with the disturbing electro-motive-forces and at which the potential differs from that of the cathode of the thermionic device, whereby an input element may have its terminals connected, respectively, to the point so defined and to the grid of the thermionic device.

Further in accordance with my invention, to avoid adjusting with nicety the magnitudes of the aforesaid inductances, or their relation to each other, there is connected in parallel with either or both of the intra-tube capacities, existing between grid and plate and between grid and cathode a supplemental capacity of suitable magnitude.

My invention resides in a system of the character hereinafter described and claimed.

This application is in part a continuation of my prior application Serial No. 653,490, filed July 24, 1923.

For an understanding of my invention, and for an illustration of some of the various forms it may take, reference may be had to the accompanying drawings, in which:

Fig. 1 is a diagrammatic view of a circuit arrangement in accordance with my invention.

Fig. 2 is a diagram of a Wheatstone bridge circuit corresponding in general with the circuit arrangement of Fig. 1.

Fig. 3 is a diagrammatic view of a multi-stage amplifier having my invention applied to the individual stages thereof and between stages remote from each other.

Fig. 4 is a diagrammatic view of a further modification of my invention.

Fig. 5 is a diagram, in the form of a Wheatstone bridge, explanatory of that form of my invention illustrated in Fig. 4.

Fig. 6 is a fragmentary diagrammatic view of a further modification corresponding in general with Fig. 4.

Referring to Fig. 1, which is a reproduction of Fig. 8 of my aforesaid application Serial No. 653,490, A and B are the terminals of or to which the input element is connected, or are the terminals between which the input energy or electro-motive-force is impressed. The terminal A connects with the grid G of the thermionic device VT, whose anode or plate is indicated at P and whose filament or cathode is indicated at F. C and D are, respectively, the output terminals or terminals in the anode circuit to which the output impedance or apparatus is connected. The battery B1 supplies current for heating the cathode F, and the battery B2 supplies the anode circuit energy.

Between a suitable point in the anode circuit, in which exist the disturbing electro-motive-forces whose reaction upon the input system is to be controlled, reduced or eliminated, and the cathode F, are connected in series with each other the inductances L3 and L4, between which there is defined a point, as O, whose potential is different from that of the cathode F and at which the potential caused by the reaction of the disturbing electro-motive-forces varies in phase with the potential of the anode P, or in general, in phase with the disturbing electro-motive-forces. The input energy is impressed between the point O and the grid G, that is, the terminals A and B of the input element are connected, respectively, to the point O and the grid G.

In series with the inductances L3 and L4 at any suitable point in the connection from the source of disturbing electro-motive-forces to the point O or cathode F is the condenser C5, serving as a stopping condenser to prevent short circuit of the source B2 through the inductances L3 and L4, and whose capacity is of such magnitude that

there is offered substantially no reactance to the oscillations or undulating currents involved.

The arrangement of Fig. 1 is in effect a true Wheatstone bridge, as exemplified in Fig. 2. The input element, such as the circuit S, comprising the inductance L and the tuning condenser K, for tuning to the frequency of the input energy, or any other 10 suitable or equivalent input element, is connected in that conjugate conductor of the bridge extending between the grid G and the aforesaid point O. The capacity between the grid and cathode of the tube VT is indicated at C1, in one arm of the bridge, and in a corresponding arm of the bridge is the capacity C2 between the grid G and anode P of the thermionic device. In the other arms of the bridge are the aforesaid inductances L3 and L4, with the condenser C5 in 15 series in the connection between the conjugate points P and F, connected, respectively, to the aforesaid terminals C and D, between which may be connected the output impedance Z of any suitable type or character, as, for example, the primary of a transformer. 20

The resistance R and the source of fluctuating electro-motive-force E, indicated in dotted lines as connected between the points P 30 and F, represent generically the internal resistance and electro-motive-force active within the tube VT in the anode circuit thereof.

The disturbing electro-motive-forces are 35 in effect impressed across the tube electrodes P and F, but their reaction upon the input element S, or equivalent, is nil when the bridge is in perfect balance, and are materially reduced when the bridge is in approximate balance.

As now well understood in the art, when the anode circuit of the thermionic device is to sufficient extent inductively reactive, the reaction upon the input system is such as to 40 in effect lessen its resistance, as by introduction of negative resistance, causing regenerative action, or in the extreme case the production of oscillations. When the anode circuit is capacitatively reactive or in effect contains only resistance, the reaction in effect 45 adds positive resistance to the input system, decreasing the effective energy impressed upon the input system.

It will accordingly be understood that my 50 system may be utilized for controlling, reducing or eliminating the reaction under any of the aforesaid conditions in the anode circuit.

While the bridge may be balanced by suitably relating to each other the magnitudes of the inductances L3 and L4, this is often of inconvenience, particularly in the production of radio receiving sets, in which it is desirable to wind the inductance coils L3 and L4 55 in great numbers and relatively inexpens-

sively, under which circumstances the magnitudes of these inductances will vary somewhat, as will also their resistances due to lack of uniformity in the conductor. It is therefore simpler and cheaper to effect the balance or desired degree of balance of the bridge by recourse to the small condensers c1 and c2 connected in parallel with the intratube capacities C1 and C2, respectively. Either or both of the condensers c1 and c2 may be utilized, 70 and a suitable magnitude for each is determined by trial for a given pair of inductances L3 and L4. 75

In Fig. 3 there is shown a radio receiving system embodying my invention and comprising the antenna H, or equivalent absorption structure, between which and the earth or counter-capacity I is connected the primary J of an oscillation transformer whose secondary is the inductance L of the input element 80 S, shunted by the tuning condenser K. With the first stage vacuum tube VT, operating as a radio frequency amplifier, are associated the inductances L3, L4, condenser C5 and small condensers c1 and c2, as in Fig. 2. As 85 indicated, one terminal of the cathode battery B1 may be connected to earth or counter-capacity I. The output impedance Z is coupled to the primary L1, shunted by the tuning condenser K1, of the second stage input element S1, which impresses the amplified energy upon the second stage radio frequency amplifier VT1, with which are associated the inductances and condensers, as in the first stage. The output impedance Z1 is inductively coupled to the input element S2 of a 90 third stage, which may be that of a further radio frequency amplifier, or of a detector tube. 95

In the arrangement of Fig. 3 there is an additional structure for controlling, reducing or eliminating reaction of disturbing electro-motive-forces of or in a remote point or stage, as, for example, the input circuit of the third stage, as illustrated, upon the input system of the first stage. In my co-pending application Serial No. 145,539, filed November 1, 1926, there is described and claimed a similar balanced network for controlling the reaction between the input and output circuits of an 100 amplifier stage, and between stages. This structure comprises an inductance L5 connected between the point O and a point at which exists a varying disturbing potential. When required, the stopping condenser C6, 105 of the character and purpose of the condenser C5, may be employed. In this instance the inductances L5 and L4 determine the point O, which is simultaneously determined by the co-action of the inductances L3 and L4. 110 Where the inductance L4 is so utilized in common with two other inductances, as L3 and L5, the elimination or suitable reduction of 115 the reaction by the remote disturbing electro-motive-force is effected by suitably propor- 120

tioning L4 to L5 for that remote disturbing electro-motive-force, in which case inductance L3 will partake of such magnitude with respect to the inductance L4 as to suitably reduce or eliminate the reaction of the adjacent disturbing electro-motive-force.

In Fig. 4 the point O is intermediate the terminals of the output impedance Z, and is connected in the conjugate conductor to the terminal B of the input element, as S or equivalent. In this connection of conjugate conductor there is provided a condenser C7, of large capacity, exhibiting very low reactance to the frequency of the current involved, to prevent impression upon the grid G of the tube VT of the potential of the positive pole of the anode circuit source B2. It will be understood that the condenser C7 may be disposed anywhere in the path between the point O and the grid G. Since in such an arrangement the grid G is insulated from the cathode F, there is utilized a high resistance R1 connecting the grid and cathode to each other. The second stage in this example comprises a detector tube VT2, in whose anode circuit is the instrument T, as a telephone, loud speaker, or the primary of an audio frequency transformer affecting coupling to the input of an audio frequency amplifier, or to the first stage of a series of audio frequency amplifiers.

In this system the two portions of the inductance Z to either side of the conjugate point O constitute the inductances of the Wheatstone bridge, as indicated in Fig. 5, and correspond, respectively, with the inductances L3 and L4 of Figs. 1 and 2. These inductances constitute the primary of an oscillation transformer in this case, whose secondary is the inductance L1 in the input system of a succeeding stage.

In Fig. 6 an arrangement generally similar to that of Fig. 4 is shown. The point O is in this case, however, disposed intermediate the terminals of the secondary L1 of the transformer whose primary is the impedance Z in the anode circuit of the tube VT. In order that the potential at the point O shall be in phase with the disturbing electro-motive-force, that end of the inductance L1 which connects with the grid of the detector tube VT2, in whose anode circuit is the same source B2 and whose cathode is heated by current from the source B1, has the same polarity as that terminal of the impedance Z which connects with the anode P of the tube VT. That is to say, the sense of winding or direction of connection of the secondary L1 shall be such that the polarity of its upper terminal shall at all times throughout successive oscillations be of the same polarity as the upper terminal of the primary Z.

For the purpose of brevity, it shall be understood that the term "control" as employed in the appended claims is considered to in-

clude a degree of control at which the effect of a disturbing potential is eliminated.

What I claim is:

1. The combination with a three electrode thermionic device having an input circuit, an impedance connected between a point in said input circuit and the cathode of said thermionic device, a second impedance connected between said point and a point of disturbing potential remote from the input and output circuits of said thermionic device, and an input element connected between said first named point and the grid of said thermionic device.

2. The combination with a three electrode thermionic device having an input circuit, an inductance connected between a point in said input circuit and the cathode of said thermionic device, a second inductance connected between said point and a point of disturbing potential remote from the input and output circuits of said thermionic device, a condenser of low reactance connected in series with said second inductance between said points, and an input element connected between said first named point and the grid of said thermionic device.

3. The combination with a three electrode thermionic device having an input circuit, an inductance connected between a point in said input circuit and the cathode of said thermionic device, a second inductance connected between said point and a source of disturbing potential, a condenser of low reactance connected in series with said second inductance between said point and said source, and an input element having its terminals connected, respectively, to said point and the grid of said thermionic device.

4. The combination with a three electrode thermionic device having an input circuit, an inductance connected between a point in said input circuit and the cathode of said thermionic device, a second inductance connected between said point and a point of disturbing potential in the anode circuit of said thermionic device, a condenser having low reactance connected in series with said second inductance between said points, and an input element having its terminals connected, respectively, to said first named point and the grid of said thermionic device.

5. The combination with a three electrode thermionic device having an input circuit, an impedance connected between a point in said input circuit and the cathode of said thermionic device, a second impedance connected between said point and a point of disturbing potential remote from the input and output circuits of said thermionic device, a third impedance connected between said first named point and a point in the anode circuit of said thermionic device, and an input element connected between said first named

point and the grid of said thermionic device.

6. The combination with a three electrode thermionic device having an input circuit, an inductance connected between a point in said input circuit and the cathode of said thermionic device, a second inductance connected between said point and a point of disturbing potential remote from the input and output circuits of said thermionic device, a third inductance connected between said first named point and a point in the anode circuit of said thermionic device, and an input element connected between said first named point and the grid of said thermionic device.

7. In a radio receiving apparatus, a thermionic amplifier having a grid, a plate and a filament, a source of current connected with said plate and filament, an input coupling transformer having a primary and a secondary winding, a connection between said plate and filament including a fixed condenser and an inductor coil, a connection between said grid and plate including the whole of the secondary winding of said input coupling transformer, a portion of said inductor coil and said fixed condenser, and a connection from said grid to said filament including a variable condenser.

8. Radio receiving apparatus comprising a three-electrode thermionic tube, a Wheatstone bridge including impedance between two of said electrodes in a balancing arm thereof, impedance between two other of said electrodes in a second balancing arm adjacent said first arm, and impedances connecting another two of said electrodes forming the remaining balancing arms of said bridge, input and output circuits for said tube included respectively in conjugate arms of said bridge, and impedance connected between a point of said bridge intermediate said last named arms and a point of disturbing potential remote from said input and output circuits.

9. Radio receiving apparatus comprising a thermionic tube having a cathode electrode and two other electrodes, a Wheatstone bridge three points of which are connected to said electrodes, and the fourth point of which is determined by impedances connected between said cathode and one of said electrodes, input and output circuits for said tube included respectively in conjugate arms of said bridge, and impedance connected between said fourth point and a point of disturbing potential remote from said input and output circuits.

10. Radio receiving apparatus comprising a thermionic tube having a cathode and two other electrodes, a Wheatstone bridge one pair of conjugate points of which are connected to said cathode and one of said electrodes, and of whose second pair of conjugate points, one is connected to the other of said

electrodes, input and output circuits for said tube included respectively in conjugate arms of said bridge, and impedance connected between the other point of said second pair of conjugate points and a point of disturbing potential remote from said input and output circuits.

In testimony whereof I have hereunto affixed my signature this 22nd day of July, 1925.

JOHN M. MILLER.
